CLAMP OPERATING TOOL

Frank C. Wallace, North Hollywood, Calif., assignor to Herman H. Helbush, Los Angeles, Calif.

Application June 26, 1944, Serial No. 542,190

4 Claims. (Cl. 29—270)

1

My present invention has to do with improvements in clamp holding and operating tools and, while it is adaptable for other uses, it is designed primarily for the purpose of holding spring-actuated sheet metal fasteners or clamps while compressing the spring which normally urges the plunger of the clamp into retracted position. For instance, fasteners of this general type are shown in my Patents Nos. 2,266,929 and 2,271,879.

Several problems have presented themselves in providing efficient tools for holding and operating such clamps. One of those problems has been the fact that an operator must frequently use clamps of different sizes and lengths and all the operating tools heretofore have been suitable for only a single length of clamp, requiring that the operator carry a plurality of operating tools and changing from one to the other as the different sized clamps are encountered, all of which requires considerable additional time and labor as well as duplication of equipment.

Another respect in which such clamp holding and operating tools have been objectionable has been their lack of any practical safety means for positively securing the fastener or clamp in the tool against accidental escape while the spring of the clamp is being compressed. Such clamps usually employ a very strong spring which must be compressed in order to protract the clamping element from the body of the clamp, and unless the clamp is meticulously centered in the holding tool, the clamp is apt to fly out laterally and strike and injure a workman. Numerous very serious accidents have resulted from this shortcoming of prior tools.

It is among the objects of my present invention to provide a holding and operating tool of this character which may be quickly and simply adjusted to take different sized fasteners.

It is another object to provide a tool of this character comprising a holding element and a plunger which are so operatively connected to an actuating lever as to be simultaneously moved in opposite directions, so that the fulcrum and consequently the manual effort necessary for operation are reduced to a minimum.

Another object is to provide a tool of this character embodying novel and highly efficient safety means for retaining a fastener in operating condition and against accidental escape from the tool.

Another object is the provision of a clamp holding and operating tool which is extremely simple and efficient in construction and operation, capable of economical manufacture and which has long life.

Still further features of novelty and advantage are provided by my invention but those will become obvious from the following detailed expla-

nation of one of the practical embodiments thereof. I wish it understood in this connection, however, that the specific details of construction which I shall now describe are merely illustrative since, with the understanding of the invention to be had therefrom, various modifications within the broader scope of the invention as defined by the claims will occur to those working in this art.

10. In connection with the following description I shall refer to the accompanying drawing, in which:

Fig. 1 is a side elevation with part of the housing removed, the device being shown in inoperative position;

Fig. 2 is a view like Fig. 1 except that the parts are shown in clamp operating position;

Fig. 3 is a section taken on line 3—3 of Fig. 2;

Fig. 4 is a top plan view taken on line 4—4 of Fig. 2, with parts broken away for illustrative purposes;

Fig. 5 is a view similar to Fig. 4 but with no parts being broken away;

Fig. 6 is a view similar to Fig. 1 but showing the clamp-receiving cradle in an adjusted position and showing a clamp in position in the tool; and

Fig. 7 is a section on line 7—7 of Fig. 5.

In the drawing I show at 5 a pistol-shaped housing or body comprised of a pair of oppositely disposed channeled sides 5a, 5b secured together by rivets 6. To facilitate assembly and to strengthen the housing I provide a guide 7 comprised of a U-shaped or channeled member whose bottom wall 7a is spot welded to the side member 5a and whose sides 7b extend above the plane of the sides of the side member 5a, to fit between the sides of the side member 5b when assembled.

40. A channeled operating lever 10 is a fulcrumed between sides 5a, 5b by a cross pin 11, the lower end 10a of the lever projecting out of the housing for manual manipulation. The upper or inner end of the lever presents bifurcations 10b. One 45 of the bifurcations has provided therethrough a curved slot 12 for the purpose to be described, the side wall of the slot providing a shoulder 12a.

A cradle member 15 of U-shaped cross section is mounted in the housing to reciprocate through the end opening 16 provided by the left-hand end of the housing, the inner or right-hand end 15a of the cradle member having a longitudinal slot 17 in its bottom wall to pass the bifurcations 10b, and said inner end provides a guideway for a plunger 20, which latter element is U-shaped in plan section and has secured to its end wall a clamp-engaging plunger element 21 which projects axially of the cradle 15 to engage the spring-pressed plunger P of a clamp A (see Fig. 6).

60. The inner ends of the lever bifurcations 10b are

pivotedly connected to the plunger element 21 by means of a link 23 and cross pins 22.

A pair of depending ears 25 are provided on the cradle member 15 by being cut from the sides thereof and bent downwardly, and between those ears the outer end of a link 26 is pivotedly connected by a pin 27. The opposite or inner end of link 26 carries a cross pin 28 which projects into the slot 12, being adjustable therealong between the positions of Figs. 2 and 6. That is, for relatively long clamps A, the pin would be set to pull against the left-hand end of the slot 12 (see Figs. 1 and 2) and for relatively short clamps the pin would pull against the other end of the slot (see Fig. 6), being prevented from accidentally escaping from the latter position of adjustment by the shoulder 12a.

From the right-hand end of the cradle member 15 there is a depending arm 29 to the outer end of which a compression spring 30 is secured as by a loop, the opposite end of the spring being anchored to the side member 5a of the housing by being looped through an eye 31 struck out of the material of the side member.

The top portions of the side members 5a, 5b at their left-hand ends are cut away as shown at 35 in Fig. 5 to permit a clamp A to be dropped into and removed from the cradle 15.

To secure the clamp A against outward longitudinal and upward lateral movement in the cradle, I inwardly emboss in each of the opposite sides of the cradle member a stop element 40, which is in the shape of an inverted L (see Fig. 2), the cradle member being long enough that the distance between the inner end of the top portion 40a of the stop element and the outer end of the plunger finger 21 is sufficient to enable that portion of the clamp A between its inner stop shoulder S and the right-hand end of the fastener plunger P to be dropped into the cradle through the open top. After being thus dropped into the cradle, a slight tipping of the cradle or a slight inward movement of the plunger finger 21 will move the stop shoulder S of the clamp into engagement with the lower portion 40b of the stop element and beneath the portion 40a thereof, so that the clamp cannot escape from the cradle until again moved to the right to clear the stop element portion 40a.

In operation, the parts of the tool are in the position shown in Fig. 1. First the clamp is dropped into the cradle 15 through the housing opening 35 and by grasping the handle portion of the housing and the lever 10 and pressing them together, the cradle member 15 and the plunger member 20 are caused to slide or telescope relative to each other—that is, the cradle member 15, by virtue of being connected to the lever below the fulcrumed end 11, is pulled inwardly, while the plunger member 20, by virtue of being connected to the lever above the fulcrumed end 11, is pushed outwardly, so that the plunger P of the clamp is forced into the body of the clamp to protract the outer end W of the clamp from the clamp body, compressing the clamp spring T. During this movement the clamp cannot laterally escape from the cradle since the sides and bottom of the latter prevent downward or sideways escape and the overhanging portion 40a of the stop element prevents upward escape. To release the clamp the operation is in the reverse direction.

If it be desired to adjust the tool to receive a short clamp, this may be accomplished by holding the lever against movement and inverting the tool while pushing inwardly on the outer end of the cradle member 15. This causes the pin 28 of the link 26 to move along the slot 12 and engage behind the shoulder 12a of the slot (see Fig. 6).

The spring 30 normally urges the parts into the inoperative position of Figs. 1 and 6, thus urging the cradle member outwardly and causing the upper end of the lever to swing to the right, moving the piston member 20 inwardly of the housing.

I claim:

1. A clamp-operating tool comprising a body, a telescopic member carried by the body, said telescopic member consisting of a pair of elements mounted for longitudinal movement in opposite directions relative to each other, one of said elements being trough-shaped to provide a U-shaped cradle presenting stop means for stationarily retaining a clamp in position to be engaged by the other element, means for simultaneously moving said elements in opposite directions, said means including a lever, and means fulcruming the lever between its ends in the body, said lever being operatively connected to one of the elements at one side of the fulcrum and operatively connected to the other element at the other side of the fulcrum.

2. A clamp-operating tool comprising a body, a telescopic member carried by the body, said telescopic member consisting of a pair of elements mounted for longitudinal movement in opposite directions relative to each other, one of said elements providing a cradle presenting means for stationarily retaining a clamp in position to be engaged by the other element, means for simultaneously moving said elements in opposite directions, said means including a lever, and means fulcruming the lever between its ends in the body, said lever being operatively connected to one of the elements at one side of the fulcrum and operatively connected to the other element at the other side of the fulcrum.

3. A clamp-operating tool comprising a body, a lever, means pivotally fulcruming the lever between its ends in the body, a cradle member reciprocally mounted in the body, a plunger member carried by the body for movement axially relative to the cradle member, means carried by the cradle member to stationarily retain a clamp in position to be engaged by the plunger member, said lever presenting a curved slot at one side of the fulcrum, a link pivotally connected at one end to the cradle member, said link having a lateral projection at its other end extending into said slot and being adjustable into positions engageable against either end of the slot, and means operatively connecting the plunger member to the lever at the other side of the fulcrum.

4. A clamp-operating tool comprising a body, a lever pivotally secured to the body, a clamp-compressing member movably carried by the body, a clamp-retaining cradle longitudinally slidably mounted in the body for movement relative to the compressing member, and means for simultaneously moving said member and cradle relative to each other comprising link elements operatively connected at one end to the cradle and clamp-compressing member, respectively, and adjustably connected at their other ends to the lever.

FRANK C. WALLACE.
